UNITED STATES PATENT OFFICE.

GEORGE J. SEISS, OF TOLEDO, OHIO, ASSIGNOR TO THE SEISS MANUFACTURING COMPANY, OF TOLEDO, OHIO, A CORPORATION OF OHIO.

BRACKET.

1,181,687.

Specification of Letters Patent. Patented May 2, 1916.

Application filed April 7, 1915. Serial No. 19,740.

To all whom it may concern:

Be it known that I, GEORGE J. SEISS, a citizen of the United States, and a resident of Toledo, in the county of Lucas and State 5 of Ohio, have invented a certain new and useful Bracket; and I do hereby declare the following to be a full, clear, and exact description of the invention, such as will enable others skilled in the art to which it ap- 10 pertains to make and use the same, reference being had to the accompanying drawings, and to the characters of reference marked thereon, which form a part of this specification.

15 My invention relates to brackets.

It particularly relates to an adjustable and interchangeable bracket for supporting devices, such as, horns, bells, lamps, etc., at any suitable angle upon a support such 20 as, a bar or stanchion or other body. It is of particular value when used in connection with bicycles, motorcycles, and automobiles for supporting lamps, horns, or bells and other alarm or sounding, or lighting devices, 25 in a position convenient and accessible to the operator or driver.

The invention may be contained in many forms of constructions usable for different purposes, all of which come within the pur- 30 view of my claims hereinafter appended. To show the practicability of my invention I have selected a bracket containing the invention as an example and shall describe it hereinafter. The bracket selected is illus- 35 trated in the accompanying drawings.

Figure 1, of the drawing illustrates a side view of the bracket, showing the horn supported in one position relative to the supporting bar. Fig. 2 is a rear view of the 40 devices illustrated in Fig. 1. Fig. 3 illustrates the bracket supporting the horn illustrated in Fig. 1, at an angle 90° to the position shown in Figs. 1 and 2. Fig. 4 illustrates the supporting member of the bracket 45 to which the device to be supported is connected. Fig. 5 illustrates in perspective one of the clamping elements of the bracket.

1, in the drawings, indicates a horn which is supported by the bracket containing my 50 invention. 2 is a suitable tube such as a brace or bar or other rod or member of a motorcycle or other machine or article on which the horn is supported and to which the bracket is attached. 3 is a U-member

having ears 4 formed on the leg 7 to which 55 the horn 1 may be secured by means of the bolts 5 which extend through the ears 4. One leg 6 of the U extends to the horn and also acts as a support at the rear end of the horn. The U supporting member or plate 3 60 is provided with four openings, slots, chan- nels or engageable edges or points adapt- ed to be engaged by clamping members lo- cated in the form of a square or in the 65 points or corners of a square. In the par- ticular form of the bracket shown the U- member is provided with four openings or slots 9 and 10 which are disposed prefer- ably in the form of a square, that is, their 70 adjacent side edges are spaced substantially equidistant from each other. The openings 9 and 10 are located in the central portion 75 of the plate and between the legs 6 and 7 of the U. Two clamping members 11 and 12, each having two lugs 13, clamp the U-mem- 80 ber 3 and the supporting body 2. The lugs 13 extend upward from the upper edge 85 of the clamping members and are bent pref- erably V-shape so as to engage with the edges of the holes 9 and 10 formed in the U- member 3 of the bracket. The lower por- 90 tion 14 of the clamping members of the bracket are preferably bent V-shape so as to engage with the tube or supporting body 2. The clamping members are also pref- 95 erably bulged along the vertical central por- tions 15 to give strength to the clamping members when they are clamped about the supporting body 2. A bolt 16 having a nut 17 extends through openings 18 formed 90 centrally and preferably near the top or vertical portion of the clamping members to clamp the bracket to the supporting body 2. The V-shaped lugs 13 of one of the clamping members may be inserted in any pair of 95 the openings 9 and 10 formed in the U- member 3 of the bracket and the other clamping member may be inserted in the other pair, that is, the lugs may be inserted in the openings 9, 9 or 10, 10 or they may be 100 inserted in the openings 9—10, and the lugs of the other member may be inserted in the remaining pair of openings which will give 105 90° angular change in the position of the supporting U-member relative to the clamping members according to the position taken by the first clamping member. The clamping members may then be drawn together

by means of the bolt 16 which will clamp the clamping members not only about the supporting body 2, but will also clamp the U-member of the bracket between the V-shaped lugs 13 which will press against the edges of the openings 9 and 10 of the U-member 3. This will permit the horn or other device to be supported either in parallel relation with respect to the supporting body 2 or at right angles to the supporting body 2. Also, the horn or other device may by this means be supported in any position about the supporting body or any position along the supporting body in the manner well known in the art.

The bracket selected and described may be greatly varied in the arrangement and manufacture of its parts and in the substitution of elements having equivalent functions and such modifications may be used for many varied purposes and still contain the invention.

Having thus described my invention, what

I claim as new, and desire to secure by Letters Patent, is,—

25

1. A supporting bracket having a supporting member, the supporting member having four square holes arranged in square formation and having parallel edges, a pair of clamping parts each part having a pair 30 of clamping tongues inserted in either pair of openings, a means for drawing and holding the parts together.

2. A supporting bracket having a supporting member, the supporting member 35 having four square holes arranged in square formation and having parallel edges, a pair of clamping parts each part having a pair of V-shaped clamping tongues and V-shaped clamping portion, a means located intermediate the clamping tongues and the V-shaped clamping portions of the parts for drawing and holding the parts together.

40

In testimony whereof, I have hereunto signed my name to this specification.

GEORGE J. SEISS.
